(57) **CLAIM**

The ornamental design for a fishing tackle storage device, as shown and described.

DESCRIPTION

FIG. 1 is a top-front perspective view of a fishing tackle storage device;

FIG. 2 is a top-rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is an interior perspective view of a lid of the fishing tackle storage device;

FIG. 10 is a front elevation view thereof;

FIG. 11 is a rear elevation view thereof;

FIG. 12 is a right elevation view thereof;

FIG. 13 is a left elevation view thereof;

FIG. 14 is a top-front perspective view showing an interior of the fishing tackle storage device with the lid removed; and,

FIG. 15 is a top-rear perspective view showing an interior of the fishing tackle storage device with the lid removed. The broken line showing of portions of the fishing tackle storage device forms no part of the claimed design.
